OF WICHITA, KANSAS.

CLASP.

1,128,601.

Specification of Letters Patent. Patented Feb. 16, 1915.

Application filed October 10, 1913. Serial No. 794,471.

To all whom it may concern:

Be it known that I, JAMES GRIEVE, a citizen of the United States, residing at Wichita, in the county of Sedgwick and State of Kansas, have invented a new and useful Clasp, of which the following is a specification.

The invention relates to improvements in clasps or clips.

10 The object of the present invention is to improve the construction of clasps or clips, and to provide a simple, practical and efficient one-piece clasp, designed for the various uses to which clips and clasps are employed, such as a necktie clasp or holder, safety chain holder for watch fobs, paper clip, etc., and presenting a plurality of engaging portions or spring clamping jaws to the article or articles engaged by it, said 20 engaging portions or jaws being located at the outer and inner ends thereof, the front or outer engaging portions or jaws exerting a relatively slight pressure on an article or articles in applying the clasp thereto, and 25 the rear engaging portions or jaws more firmly gripping the article or articles in the final adjustment of the clasp and also serving to increase the pressure of the front engaging portions.

30 With these and other objects in view, the invention consists in the construction and novel combination of parts hereinafter fully described, illustrated in the accompanying drawing, and pointed out in the claim here- 35 to appended; it being understood that various changes in the form, proportion, size and minor details of construction, within the scope of the claim, may be resorted to without departing from the spirit or sacrificing any of the advantages of the invention.

In the drawing:—Figure 1 is a perspective view of a clasp, constructed in accordance with this invention. Fig. 2 is a plan view of the same. Fig. 3 is a longitudinal 45 sectional view of the clasp. Fig. 4 is a plan view of the blank from which the clasp is formed.

Like numerals of reference designate corresponding parts in all the figures of the drawing.

In the accompanying drawing in which is illustrated the preferred embodiment of the invention, the clasp is constructed of a single strip or blank of sheet metal, or any 55 other suitable material having sufficient

resiliency for the purpose, bent at an intermediate point to form a back 1, a front clamping jaw 2 and a connecting bend 3. The back 1, which is preferably oblong, as shown, constitutes a jaw or member and coacts with the front jaw or member 2 in clamping an article, but the back may be of any other preferred configuration, and in practice the clasp may be constructed of precious metal as well as base metal and may be embossed and engraved or ornamented with emblems or any other ornamentation to provide an artistic device. The connecting bend is preferably curved, as shown, and the outer or front jaw or engaging member 2 is arranged at an acute angle to the back 1 and its free terminal 4 is preferably curved outwardly to form a flaring entrance to enable an article to be readily introduced between the two clamping jaws or members. To further facilitate this the back 1 is extended at its free end 5 beyond the outwardly curved free terminal 4 of the front jaw or member 2. At opposite sides of the center of the front jaw or member 2 it is provided with longitudinal slits 6 which are formed by stamping or otherwise cutting the material, said slits extending inwardly from the side edges of the front jaw and longitudinally of the same 85 from points adjacent to the bend along the front jaw or member and terminating short of the transverse edge of the free end 4 of the same, thereby leaving the free end 4 the full width of the strip and providing side 90 springs 7, which have free inner terminals 8 bent or bowed outwardly. Owing to the fact that the slits converge toward the outer end of the jaw or member 2, the side springs 7 taper inwardly while the front jaw or 95 member 2 tapers outwardly, the parts being connected by an integral terminal clip formed by the said free end 4. The terminals 8, which are preferably tapered, are curved outwardly, as clearly shown in Fig. 100 3 of the drawing, and the inner portions of the side springs are arranged at an obtuse angle to the outer portion of the front jaw and at an acute angle to the inner portion of the same.

The free ends 4 and 5 of the jaw or member of the clasp form front clamping portions and are adapted to exert a relatively light pressure on an article, which preliminary pressure serves as a convenient means for 110

holding the clasp in position on the shirt while adjusting the necktie to the same enabling the necktie to be readily placed within the front portion of the clasp. The 5 final adjustment of the clasp is effected by slipping the same inwardly on the shirt bringing either the shirt, or both the shirt and the necktie, between the inner clamping portions, formed by the free terminals of 10 the side springs and the inner portion of the back. The inner or rear clamping portions are adapted to firmly grip an article, and at the same time the outward movement of the inner free ends of the side springs tends to 15 force the outer end of the front jaw inwardly and increase the pressure at the front of the clasp.

The clasp presents smooth surfaces devoid 20 of any sharp points or edges to the articles gripped, whereby the clasp may be easily applied in position and in clamping engagement and readily removed therefrom without injuring fabrics or other articles. The 25 solid imperforate back of the clasp forms a strong and durable supporting member to coöperate with the front clamping jaw and the side springs.

What is claimed is:—

A clasp consisting of a single oblong strip 30 or blank of resilient metal bent transversely

at an intermediate point to form a back, a front jaw, and a connecting bend, the front jaw being arranged at an acute angle to the back and having its free end bearing against the inner face of the same and curved outwardly therefrom, said front jaw having converging longitudinal slits extending inwardly from the side edges of the front jaw and along the same to and terminating adjacent the said free end of the front jaw, 40 leaving the latter the entire width of the strip, said slits forming side springs, said springs being bowed at an intermediate point and having their inner portions arranged at an angle to the back and bearing 45 at their free ends against the inner face of the said back, the free ends of the side springs and the free end of the front jaw forming inner and outer clamping portions, and the inner clamping portions, when put 50 under tension, increasing the pressure of the front clamping portion.

In testimony that I claim the foregoing as my own, I have hereto affixed my signature in the presence of two witnesses.

JAMES GRIEVE.
